UNITED STATES PATENT OFFICE.

HARRY B. SNELL, OF SOUTH BEND, INDIANA, ASSIGNOR OF ONE-FOURTH TO WILLIAM HOWARD EDWARDS AND ONE-FOURTH TO FRANK E. WHITEHALL, BOTH OF SOUTH BEND, INDIANA.

ALTERNATING-CURRENT RECTIFIER.

1,326,698.

Specification of Letters Patent. Patented Dec. 30, 1919.

Application filed February 3, 1916. Serial No. 76,007.

To all whom it may concern:

Be it known that I, HARRY B. SNELL, a citizen of the United States, residing at South Bend, in the county of St. Joseph and State 5 of Indiana, have invented certain new and useful Improvements in Alternating-Current Rectifiers, of which the following is a specification.

My invention relates to improvements in 10 alternating current rectifiers more especially adapted to Ford automobiles and it appertains specifically to the features pointed out in the annexed claims.

The purpose of my invention is to provide 15 a rectifying system that will change the alternating current from multipolar or other magnetos into a unidirectional current suitable for charging storage batteries in connection with automobile service; that will 20 automatically control itself without the use of automatic cut outs, voltage switches, etc.; that will provide a separate storage capacity for each sign of the A. C. magneto current; that will use the magneto current 25 efficiently at all changes of periodicity; and that will positively synchronize the pole changing contacts with the periodicity of the current impulses.

With these and other ends in view I illustrate 30 in the accompanying drawing such an instance of adaptation as will disclose the fundamental features without limiting myself to the specific details shown.

The means heretofore used have attempted 35 to change both sides of the current through complicated duplex contacts, etc., for each sign or through a simple electrical vibrator that effectively collects one sign only of the current and ignores the 40 other. With my system both signs are completely used without having recourse to complex mechanisms.

Figure 1— is a diagrammatic view of the 45 interrelated mechanism and circuits.

Fig. 2— is a plan view, partly diagrammatic of a mechanical synchronous pole changer.

Fig. 3— is a diagrammatic view of Fig. 2 in a different setting.

Fig. 4— is an elevation in section of the assembled parts of a complete apparatus also showing the usual distributor mechanism attached to a rectifier.

In carrying out my invention I provide a fiber disk 22 having teeth 29 formed on its 55 periphery. It is secured on shaft 7 by means of pins 23 so as to rotate with it. The disk or cam as it might be called has 16 teeth which correspond with the poles of the magneto 1. It is rotated in mechanical synchronism with the rotation of the magneto which is secured to the main shaft 3 of engine 2. The usual 2:1 gears connect the cam or valve shaft 4 to the shaft 3. Miter gears 5 connect the vertical shaft 7 to 60 shaft 4. This vertical shaft has bearing in the bracket 6. At its upper end this bracket has a slot 8 formed therein beneath hub 10. From this it will be seen that the teeth 29 of cam 22 will accommodate eight impulses 65 of a positive sign and eight impulses of a negative sign for each revolution of the disk.

The positive currents generated by magneto 1 traverse line 51 to terminal 43 connected to pivot pin 27 on which bearing block 28 with its attached arms 55 and 56 has movement. From this point the current traverses spring 44, platinum contact 34 and the positive contact screw 36 of 70 binding post 46 which is connected to the positive terminal 49 of the positive half 42 of the storage battery 40 by wire 53 because the V shaped shoe 30 of arm 56 is at the bottom of the groove between two teeth 75 29 as shown in Fig. 3. This position of the shoe causes limit projection 31 of arm 56 to hold spring 44' away from the negative screw 35. The positive currents enter the battery as stated and pass through leaving their 80 electrolytic effect on the battery plates and leave the battery over negative terminal 48' and thence to the neutral terminal 47, line 50 to ground and back to magneto 1 thus completing the circuit for every positive 85 sign of the currents, whenever shoe 30 is found between two teeth 29 of disk 22 through a pull of spring 54 attached to the interrupter arm 56.

The negative currents generated by the 100 magneto 1 pass by way of ground wire 50 to the neutral terminal 47, thence to the positive terminal 49' through the battery leaving their "charge" on the plates of the negative half 41 of the battery 40. They pass out 105 over negative terminal 48, and wire 52 to

terminal 45 of contact screw 35, thence over platinum contact 34 and spring 44' as shown in Fig. 2, the return to magneto 1 being over wire 51. This is brought about when 5 shoe 30 is on top of a tooth 29 of disk 22 and the arm 56 has moved farther from the center of the disk 22, leaving its limit end 31 away from spring 44' thus permitting the spring to contact with screw 35. At the 10 same time arm 55 through its limit end 31 holds spring 44 away from contact screw 36.

In order that springs 44 and 44' do not set up independent vibrations, arms 55 and 56 have limit stops 33 adapted to prevent any 15 excessive movement of the springs. Arms 55 and 56 are secured to block 28 by screws 32. Wires 50 and 51 serve for both negative and positive currents.

The interrupter arms are pivoted to pin 27, see Fig. 4 which is insulated from the base 12. This base has a downward projection 13 that extends into hub 10 of bracket 6. It has a groove 14 engaged by set screw 11. Shaft 7 is prevented from moving end- 25 wise by collar 9, secured thereto, placed in slot 8. The purpose of set screw 11 is to hold base 12 with its interrupter arms from having rotary movement. When starting the device set screw 11 is loosened and case 30 12 slightly turned to and fro while the cam disk 22 is in full rotation until arms 55 and 56, their contacts 35 and 36 in relation to teeth 29 of disk 22 are properly synchronized with the positive and negative signs 35 of the currents at their position of maximum working amplitude. After this position has been found set screw 11 is tightened and the parts are thereby held in continuous working relation. If the position of the 40 contacts was changed so that a zero point of the current wave coincided with the moment of contact, no current would be found in lines 52 and 53.

This device is more especially designed 45 for automobile use and it is very important that the synchronizing be accomplished speedily, without trial and error annoyances involved in repeated starting, testing, stopping, etc., to this end the adjustment must 50 be made while the cam disk 22 is rotating at full speed. Without this provision it is practically impossible to secure the proper working relation of the interruptions produced by the cam to the periodicity of the 55 alternating current supplied by the magneto 1. These features while more especially adapted to automobile uses are also available for stationary power plants, in which this facility for quickly adjusting the synchronizing relation is valuable because an expert 60 electrician is not required to set the rectifying device into operation.

A slip joint or coupling on the shaft 3 if made in two parts, or the shifting of a 65 pinned bevel gear 5 to secure synchronism

would be an impracticable expedient because it could only be done—guessed at—when the parts remained at rest. The delicacy of this adjustment will be apparent when it is recalled that in systems known 70 to the prior art only about one-fourth as many breaks are set up per each revolution of the cam shaft as in my system, consequently such means as might serve the prior art would be practically worthless in this 75 system. The setting of the contacts at the proper point with relation to the teeth of the cam and the inflexible relation of the position of these teeth to the peaks of the positive and negative portions of the waves 80 is a matter of refinement and delicacy of operation, without which the services of an expert would invariably be required, but with the provision herein instanced the problem is relatively an easy one for even 85 an inexperienced person to solve.

Battery 40 may serve the usual lamps 57 simultaneously because of its relative low internal resistance in comparison to that of the lamps. It is also available for ignition 90 purposes through the usual form of distributor, inclosed in casing 16 and coils 58 suitably connected to the several spark plugs of the engine. A cover 15 having a clearance hole for 24 is placed on base 12 and on it 95 rests the distributor casing 16 as shown in Fig. 4.

Shaft 7 imparts movement to the distributor arm 19 pivoted at 59 to hub 21 which is secured to an extension 26 indirectly attached to shaft 7 as follows: An insulated cap or bushing 25 is placed over the end of the shaft 7 and over this is placed the socket end 24 of extension 26. It has a suitable flange resting on disk 22 to which it is fastened as desired by screws, etc. The arm 19 carries contact wheel 18 which is held against the inner face of casing 16 by spring 20 in the usual manner. Wheel 18 engages segments 17—one for each cylinder—as it 110 is carried around by shaft 7. Each segment 17 is connected to a binding post 39 for each spark plug.

A current path to 24, 21, 18 and 17 is provided over contact spring 38 which engages 115 24. This spring is secured to insulated terminal 37, which in the instance shown leads to the negative terminal 48 of the battery. The casing 16 with base cover 15 is held on 12 against accidental displacement in any 120 suitable manner without interfering with the free movement of the casing to and fro under the control of a spark advance and retard rod 60 whose control lever is usually found on the steering wheel.

With this arrangement of parts a highly efficient rectifying system is obtained without the usual loss of one or the other signs of the current wave and without the complexity of so called rectifiers which depend 130

on electromagnets for their synchronous action with the fundamental periodicity of the generator.

What I claim is,

- 5 1. A source of alternating currents, a rotative vibrator cam, a storage battery, comprising two distinct groups of equal working potential, means adapted through the movement of the cam to automatically direct impulses of positive sign to the positive terminal of the battery and impulses of negative sign to the negative terminal of said battery, means adapted to ground the battery groups over a connection common to both, 10 means adapted to adjust the vibrations produced by the cam into synchronism with the alternating current while the parts are in motion, and means for locking the same after the adjustment has been made.
- 20 2. The combination with a source of alternating current, of a fixed contact member connected to each terminal of said source, a movable member adapted to move between the fixed contacts, a rotatable cam adapted to actuate the movable member, means for rotating the cam synchronously with the alternating current whereby the movable member is caused to vibrate asynchronously with said alternating current 25 30 source, means for adjusting the position of the cam and movable member with respect to each other while the cam is being rotated to secure such synchronism, and means for maintaining the same.
- 35 3. In automobile automatic lighting systems, an engine, an alternating current magneto operated thereby, a cam rotated by the engine, projections on the cam coördinated with the periodicity of the alternating current, a two section storage battery, a moving member operated by the cam, stationary contacts adjacent the said member, connections therefrom to the battery, a ground connection common to both sections of the 40 45 battery, and means for adjusting the time of

contact into synchronism with the alternating current while the cam is under normal rotation whereby impulses of positive sign will be directed to the positive terminal of the battery and impulses of negative sign to the negative terminal thereof.

4. In current rectifiers, a source of alternating current, means for imparting motion thereto, a plurality of contacts, means for opening and closing the same, means for mechanically synchronizing the control of the contacts with the periodicity of the current while the parts are in motion, a battery comprising independent storage capacity for each sign of the alternating current, 55 and suitable connections therefrom to the synchronized contacts.

5. A mechanically vibrating arm, a suitable pivot therefor, independent contacts carried by the arm, a cam adapted to set 60 the arm into periodic vibration, a source of alternating current, mechanical connections from the same to the cam so as to cause the vibrations to be asynchronous with the periods of the alternating current, independent means operable while the cam is in action for adjusting the contacts in relation to the cam so as to cause the activity of the contacts to coincide respectively with the maximum amplitude of each sign of the current wave, a storage battery having separate positive and negative sections, connections therefrom to the respective contacts whereby the positive impulses are stored in one section and the negative impulses in the other section, and suitable connections between them adapted to place them in series with each other for discharge.

In testimony whereof I affix my signature in presence of two witnesses.

HARRY B. SNELL.
